UNITED STATES PATENT OFFICE.

CHARLES PHELPS, OF OSKALOOSA, IOWA.

MOLDER'S FLASK.

SPECIFICATION forming part of Letters Patent No. 760,016, dated May 17, 1904.

Application filed May 19, 1903. Serial No. 157,835. (No model.)

To all whom it may concern:

Be it known that I, CHARLES PHELPS, a citizen of the United States, residing at Oskaloosa, in the county of Mahaska and State of Iowa, 5 have invented certain new and useful Improvements in Molders' Flasks, of which the following is a specification.

The objects of my invention are to provide a device of simple and inexpensive construction especially designed for use in casting end portions on a hollow or tubular body portion, so that the molten metal will run into the hollow ends only to a certain predetermined point and so that the metal will not 10 fill the hollow body portion, and to accomplish this desirable result without placing cores or plugs in the ends of the hollow body portion.

More specifically, it is my object to provide 15 a rigid frame having identical parallel heads fixed to its ends, each head serving as a clamp to firmly secure one end of the hollow body portion to hold its ends parallel with said heads and its sides parallel with the sides of 20 the frame, so that when heads are cast on the body portion they will be accurately positioned, and, further, to provide heads of this class each of which coact with a single flask-section having mold-cavities formed therein 25 and so arranged that the portion of the body projecting beyond the head will enter the mold-cavity and when metal is poured into the mold-cavity a head will be cast integral with the body portion and the molten metal 30 will fill the interior of the body portion to a point flush with the lower edge of the head and the said lower edge of the head will act as a chill for the adjacent surface of the head being cast to the end that any number of articles 35 may be cast in the flask and all of them will have their head portions exactly parallel with each other and at the same distance apart.

My invention consists in the construction, 40 arrangement, and combination of the various parts of the device whereby the objects contemplated are attained, as hereinafter more fully set forth, pointed out in my claims, and illustrated in the accompanying drawings, in 45 which—

Figure 1 shows in perspective the frame of the device, also showing a radiator-section in position in the frame. Fig. 2 shows in perspective one of the flask-sections with a matrix formed therein. Fig. 3 shows a transverse 55 sectional view through one of the heads of the frame.

Referring to the accompanying drawings, I have used the reference-numeral 10 to indicate the parallel sides of the rigid metal 60 frame connected and braced by a cross-piece 11. Rigidly secured to each end of the parallel side pieces 10 is a flat plate 12, having a longitudinal rib 13 at right angles thereto. Formed on the plate 12 are two lugs 14 at the 65 corners thereof, said lugs 14 and the rib 13 being provided with openings through which the bolts 15 are passed, said bolts being parallel and standing at right angles to the frame part 10. Formed on the outer face of the 70 rib 13 are two lugs 16. The outer edges of these lugs are straight and in alinement with each other, and each lug is provided with an opening 17 for purposes hereinafter made clear. 75

The device just described forms one member of the clamp, of which the coacting member consists of the flat plate 18, having a longitudinal rib 19 at right angles to the flat plate and also having perforated lugs 20 on its 80 ends, said rib 19 being also provided with perforations to receive the bolts 15, and the plate 18 is provided with a notch 21, through which molten metal may be poured. When the plate 18 is placed on the bolts 15, the adjacent faces of the ribs 13 and 19 are parallel and the surfaces of the plates 12 and 18 are flat and parallel, as clearly illustrated in Fig. 3. 85

The reference-numeral 22 indicates a flask-section of rectangular outline and composed 90 of sides and ends, and on each end is a guide-pin 23 to coact with the openings 17 before described.

In practical use two similar flasks are used. Each flask is filled with sand and a mold-cavity 95 formed therein open at the top. This is done in the ordinary way, particular care being taken to have said mold-cavity formed at a certain predetermined position with relation to the guide-pins 23. Assuming that it is de- 100

sired to use my improved flask in casting head portions on hollow sheet-metal radiator-bodies having open ends between the sheet-metal sides, I form mold-cavities to produce head portions for a radiator-body of proper size and shape. The clamp members on the frame are shaped with particular reference to the kind of articles with which they are intended to be used, and where the use is in connection with sheet-metal radiator-body portions the lugs 16 project outwardly from the rib 13 far enough to permit the rib 19 to engage the side of the body portion firmly before it strikes the said lugs. This will bring the ribs 13 and 19 to exactly parallel positions before they are stopped by the said lugs, and yet the body portion of the radiator will be firmly clamped between them. In addition to this the length of the lugs 16 is such that the inner ends of said lugs will engage the edges of said body portion, so that when a radiator-body portion is placed in position its ends will be exactly parallel with the outer surfaces of the plates 12 and 18 and its sides will be exactly parallel with the frame members 10, because the lugs 16 will serve as guides to securely hold them in this position. I then place the frame having the radiator-body portion clamped therein on top of the flask-section, the guide-pins 23 entering the openings 17. Obviously if the mold-cavities are formed in the flask-section with particular reference to their position relative to the guide-pins then the radiator-body portions will have the heads cast thereon in proper position, because the same guide-pins serve to determine the relative position of the body portion to the mold-cavities. I then pour the molten metal into the flask through the notch 21 and continue to pour it until the molten metal reaches the under surface of the plates 12 and 18. This forms a chill for the molten metal, making its edges smooth and free from imperfections, and the interior of the hollow body portion is filled with metal to a level with the under surfaces of the parts 12 and 18. This makes it unnecessary to use cores on the interior of the section. As soon as the metal is set I grasp the frame, remove it from the flask, and reverse its position and place the opposite end of the frame upon a similar flask-section, and the head is cast on the other end of the radiator-body portion in the same way. These cast heads of the body portions will of necessity be exactly parallel, and if a number of radiator-sections are cast by the use of the same frame the heads of all of the sections will necessarily be exactly parallel with each other and the sections will be of exactly the same length. As soon as both heads are cast on the body portion the movable clamping members are detached and the radiator-section removed from the frame.

Having thus described my invention, what

I claim, and desire to secure by Letters Patent of the United States therefor, is—

1. In a device of the class described, a frame, a clamp at one end of the frame to secure articles to the frame, a flask-section and coacting guiding devices on the flask and clamp. 70

2. In a device of the class described, a frame, means for securing articles to the frame, a flask-section and coacting guiding devices on the flask and frame.

3. In a device of the class described, a frame, 75 means for securing articles to the frame, a flask-section and registering guides on the flask-section and frame.

4. In a device of the class described, a flask-section, a guide on the flask-section for determining the location of mold-cavities in the flask-section, a frame, means for clamping articles to the frame and guide devices on the frame, coacting with those on the flask. 80

5. In a device of the class described, a frame, 85 a stationary clamping member thereon, a movable clamping member coacting with the stationary clamping member, a flask-section and registering guides on the stationary clamping member and the flask-section. 90

6. In a device of the class described, a frame, a stationary clamping member thereon having guide-openings, a movable clamping member coacting with the stationary member, a flask-section and guide-pins on the section to 95 enter the opening in the stationary clamping member.

7. In a device of the class described, a frame, a stationary gripping member on one end of the frame, a movable gripping member detachably secured to the stationary gripping member, the adjacent faces of the gripping members shaped to conform to the article to be clamped. 100

8. In a device of the class described, a frame, 105 a stationary gripping member on one end of the frame, a movable gripping member detachably secured to the stationary gripping member, the adjacent faces of the gripping members shaped to conform to the article to be clamped, a flask and coacting guide devices on the flask and stationary gripping member.

9. In a device of the class described, the combination of a stationary gripping member, and a movable gripping member having their adjacent faces shaped to conform to the article to be clamped, projections on the adjacent faces of said gripping members to engage the edges of the article to be clamped and to limit the movement of the gripping members toward each other, a flask and coacting guide devices on the flask and the stationary gripping member. 115 120

10. In a device of the class described, the combination of two gripping members, means 125 for forcing them toward each other, the adjacent faces of the gripping members shaped to engage the article to be clamped, projec-

tions on said gripping members to limit their movement toward each other, a flask and coacting guiding devices on the flask and one of the gripping members.

5 11. In a device of the class described, a gripping member having a flat under surface and a flat side face at right angles to the under surface, projections on the side face thereof, bolts connected with the gripping member 10 and extended parallel with the under face thereof, a mating gripping member having a flat under face and a flat face adjacent to that of the first member, and also having openings therein to receive the bolts, a flask-section and coacting guiding devices on the flask-section and one of the gripping members.

12. In a device of the class described, a frame, means for clamping an article to the frame, a flask-section and registering guide 20 devices on the flask-section and both ends of the frame.

13. In a device of the class described, a flask-section having guide-pins at its top, a frame, a gripping device at each end of the frame, 25 each gripping device having openings to receive said projections.

14. In a device of the class described, a flask-section, guide-pins thereon, a frame, a gripping device at each end of the frame having 30 a stationary and a movable member, said stationary members having openings therein to receive said guide-pins.

15. In a device of the class described, the combination of a frame, a stationary gripping 35 member fixed to each end of the frame, a movable gripping member at each end of the frame and means for clamping the movable members to the stationary ones, projections on the adjacent faces of each pair of gripping members, 40 guide-openings in said projections and a flask-section having guide-pins thereon to enter the openings in the projections.

16. In a device of the class described, a flask-section, guide-pins thereon, a frame, clamping 45 members on the frame, said clamping members resting on the flask-section and forming a top for the flask-section, and a guide device on the clamping members coacting with that on the flask.

50 17. In a device of the class described, an open-topped flask-section, a pair of coacting clamping members resting on the flask-section and forming a top for said section and coacting guide devices on the flask-section and the clamping members.

55 18. The combination, with a flask-section of two clamping members shaped to receive an article between them, and having their under faces shaped to form a mold for the top of a casting made in the flask.

60 19. The combination, with a flask-section of two clamping members, one movable to and from the other, their adjacent faces shaped to fit the article to be clamped, and their under faces shaped to form the top of the flask and

to determine the shape of the top of an article being cast in the flask-section.

20. The combination, with a flask-section of two clamping members one movable to and from the other, their adjacent faces shaped to fit the article to be clamped, and their under faces shaped to form the top of the flask and to determine the shape of the top of an article being cast in the flask-section, projections on one of the clamping members to limit the movement of the other member relative thereto.

21. In a device of the class described, an open-topped flask-section, a frame, two clamping members on each end of the frame, shaped 80 to receive an article between them and having their outer faces shaped to form the top surface of the article being cast in the flask.

22. In a device of the class described, the combination with an open-topped flask-section, of a frame, two clamping members on each end of the frame, movable to and from each other, their adjacent faces shaped to fit the article to be clamped and their outer faces shaped to coact with the flask and determine 90 the shape of the top of an article being cast in the flask.

23. The combination, with a flask-section, of two clamping members shaped to receive an article between them, and having their under 95 faces shaped to form a mold for the top of a casting made in the flask, and coacting guide devices on the flask and the clamping members.

24. The combination, with a flask-section of two clamping members one movable to and from the other, their adjacent faces shaped to fit the article to be clamped, and their under faces shaped to form the top of the flask and to determine the shape of the top of an article being cast in the flask-section, and coacting 105 guide devices on the flask and the clamping members.

25. The combination, with a flask-section of two clamping members one movable to and from the other, their adjacent faces shaped to fit the article to be clamped, and their under faces shaped to form the top of the flask and to determine the shape of the top of an article being cast in the flask-section, projections 115 on one of the clamping members to limit the movement of the other member relative thereto, and coacting guide devices on the flask and the clamping members.

26. In a device of the class described, the combination with an open-topped flask-section, of a frame, two clamping members on each end of the frame, movable to and from each other, their adjacent faces shaped to fit the article to be clamped and their outer 120 faces shaped to coact with the flask and determine the shape of the top of the article being cast in the flask, guide-pins on the flask-section and coacting guide-openings on the clamping members at each end of the frame. 130

27. The combination, with a flask-section of two clamping members shaped to receive an article between them and having their under faces shaped to form a mold for the top of the casting made in the flask, guide-pins on the flask-section and coacting guide-openings on the clamping members at each end of the

frame, and coacting guide devices on the flask and the clamping members.

CHARLES PHELPS.
